H. J. CLARK.
SUCTION MOUTHPIECE FOR DREDGES.
APPLICATION FILED APR. 23, 1908.

909,062.

Patented Jan. 5, 1909.

UNITED STATES PATENT OFFICE.

HORACE J. CLARK, OF CHICAGO, ILLINOIS, ASSIGNOR TO CLARK DREDGE MANUFACTURING COMPANY, OF CHICAGO, ILLINOIS, A CORPORATION OF MAINE.

SUCTION-MOUTHPIECE FOR DREDGES.

No. 909,062.

Specification of Letters Patent.

Patented Jan. 5, 1909.

Application filed April 23, 1908. Serial No. 428,824.

To all whom it may concern:

Be it known that I, HORACE J. CLARK, a citizen of the United States, residing at Chicago, county of Cook, and State of Illinois, have invented certain new and useful Improvements in Suction-Mouthpieces for Dredges, of which the following is a specification, reference being had therein to the accompanying drawing.

10 This invention relates to a suction mouth-piece for dredges, and particularly to an oscillating scoop construction adapted for gold dredging purposes.

The invention has for an object to provide 15 an improved construction of suction mouth-piece embodying oppositely disposed scoops each communicating with a suction pipe, and a coöperating shifting valve mounted to automatically close the inlet from either 20 scoop and also in its movement to dislodge from the inlet openings any stones or other objects which would collect and interfere with the suction action.

Another object of the invention is to provide 25 a disk or semispherical scoop having a central opening communicating with a suction pipe and mounted for adjustment upon its support so that in the event of wear or injury the entire peripheral surface thereof 30 may be used.

A further object of the invention is to provide the scoops with a projecting operating bar which is shifted by the contact of material with the scoop so as to operate the valve 35 to close the opening of the opposite scoop into the suction pipe.

Other and further objects and advantages of the invention will be hereinafter fully set forth and the novel features thereof defined 40 by the appended claims.

In the drawing:—Figure 1 is an elevation of a dredge having the invention applied thereto; Fig. 2 is an enlarged vertical section through the suction pipe and scoops; 45 Fig. 3 is a front elevation of these parts; Fig. 4 is a detail section on line 4—4, Fig. 3; Fig. 5 is a detail perspective of the valve and its operating bar.

Like numerals refer to like parts in the 50 several views of the drawing.

The invention is adapted for application to any form of dredge having a suction action, and is here shown as mounted upon a hull 10 of any desired construction which is

provided at one end with a holding spud 11 55 and at its opposite end with a depending beam 12 carrying the suction pipe 13. At the opposite ends of this beam the eccentrically disposed wheels 14 and 15 are mounted for movement and are connected by a 60 cable 16 so as to impart to the scoops an oscillatory movement. In the present instance the cable is wound upon the eccentric wheels for several turns, and one of the strands thereof is secured at 17 to the wheel 65 14 by a staple or other fastening device so that the complete rotation of the wheel is prevented, and each of the wheels is retained in the same relative position so as to secure the leverage necessary for raising the scoop. 70 Other means for securing such a leverage and oscillatory movement may be used if desired. The suction pipe 13 is connected at its upper end with any desired form of pump 18 which discharges through the conducting pipe 19 75 into the screening device as indicated at 20. The beam 12 is adapted to be raised and lowered by a block and tackle connection, as shown at 21 which is supported at the bow 80 of the boat on the beam 22.

The scoops are pivotally mounted by any preferred means at the lower end of the beam 12 and in case one of these beams is used at each side of the hull a connecting beam 25 forms the support for the scoops. In that 85 case this beam is provided with the bearing 26 to receive one end 27 of the suction pipe 13 which pipe is provided with an elbow 28 having a trunnion 29 extended therefrom and journaled in the bearing 30 carried by the 90 beam 25. The eccentric wheel 15 is secured to the portion 27 of the suction pipe and the suction pipe 13 communicates therewith through the bearing 29. Secured to the elbow section 28 is a bearing block 30 having 95 curved outer faces to support the scoops 31 which are secured thereto in any desired manner. Within this bearing block a lining sleeve 32 is disposed and is formed of suitable hard material such as manganese steel 100 to withstand the wear upon these parts. The scoops are formed of cup shaped disks substantially semispherical in configuration and each provided with a port 33 communicating with the suction pipe. These scoops 105 are also mounted so as to be rotatably adjusted in position and thereby compensate for the wear thereon. The lower portion of

the scoop is provided with the usual cutting teeth or blades 34 bolted thereon and which are removed and replaced in the adjustment of the scoops which are each provided with 5 suitable apertures 35 to receive the securing devices for these cutters. Within the suction pipe and coöperating with the opposite ports 33 is a valve 36 having seating faces at opposite sides of the standard 37 thereon, 10 which standard is carried upon a slide bar 38 mounted in the bearing 30 and formed of such length that the outer end portions 39 thereof are projected beyond the inner periphery of one of the scoops when the opposite 15 end is flush with the periphery of the opposite scoop, thus shifting the valve faces from one port to the other by contact of the material with the ends of this bar. In order to remove stones or other obstructions which in 20 the suction action may clog the ports 33, the valve is also provided with projections 40 which in their travel extend into the ports and effectually force out obstructions therefrom. For the purpose of permitting the application 25 of this bar in any of the adjustments of the scoops a series of openings 41 is provided therein at proper intervals through which the ends 39 of the slide bar may extend.

In the operation of the invention it will be 30 seen that the scoop in rising in its oscillatory movement from the position shown in Fig. 1 to a substantially horizontal plane catches and directs all of the material directly toward the central port of the scoop into which 35 it enters by gravity assisted by the suction action, and in this movement the valve is shifted so as to completely close the port of the lower scoop, while in the returning action the same operation is performed thus materially increasing the capacity of the scoop. 40

It has been found impracticable to pick up and convey particles of gold or heavy metals by the ordinary scoop constructions which agitate the material and force the gold below the area of suction, while the present 45 construction digs into and beneath the material forcing it with all contained values directly into the suction pipe and digs both upwardly and downwardly under the control of a single operator thus delivering sufficient material to supply the maximum capacity 50 of pump. The degree of oscillation of these scoops may be varied as found desirable, the present construction being shown 55 to prevent the complete rotation thereof, as the attachment of the cables to the wheels controls their relation to each other and secures the necessary oscillation by the unwinding of the remaining portions of the 60 strands.

The valve construction is automatic in its operation, not only controlling the ports but also removing stones or other obstructions which may collect and clog the ports during 65 the dredging action.

Having described my invention and set forth its merits, what I claim and desire to secure by Letters Patent is:—

1. A suction mouthpiece comprising oppositely disposed scoops, a suction pipe communicating therewith, and a shifting valve mounted to close the inlet from either scoop. 70
2. A suction mouthpiece comprising oppositely disposed scoops, a suction pipe communicating therewith, and an automatically shifting valve mounted to close the inlet from either scoop. 75
3. A suction mouthpiece comprising oppositely disposed scoops, a suction pipe communicating therewith and a shifting valve 80 mounted to close the inlet from either scoop and having means disposed to be operated by the material in the scoop.
4. A suction mouthpiece comprising oppositely disposed scoops, a suction pipe communicating with said scoops, and a slide bar 85 having a valve disk adapted to close the communicating opening from either scoop.
5. A suction mouthpiece comprising oppositely disposed scoops, a suction pipe communicating with said scoops, and a slide bar 90 having a valve disk adapted to close the communicating opening from either scoop said bar being extended beyond the face of one of the scoops. 95
6. In a suction mouthpiece, oppositely disposed disk scoops each having a central opening, a suction pipe disposed between said scoops and communicating with said openings, and a valve disposed in said pipe to automatically close either opening. 100
7. In a suction mouthpiece, oppositely disposed disk scoops each having a central opening, a suction pipe disposed between said scoops and communicating with said openings, a valve disposed in said pipe to automatically close either opening, and a slide bar connected to said valve and disposed to project beyond the inner face of one of the scoops. 110
8. In a suction mouthpiece, oppositely disposed disk scoops each having a central opening, a suction pipe disposed between said scoops and communicating with said openings, a valve disposed in said pipe to automatically close either opening, a slide bar connected to said valve and disposed to project beyond the inner face of one of the scoops, and a cutter blade disposed upon the periphery of said scoops. 115
9. In a suction mouthpiece, a suction pipe, a scoop having an opening to communicate therewith, and a bearing block secured to said pipe and upon which said scoop is adjustably mounted. 120
10. In a suction mouthpiece, a suction pipe, a scoop having an opening to communicate therewith, a valve controlling said opening, and means carried by said valve to remove obstructions from said opening. 130

11. In a suction mouthpiece, a suction pipe, and a semispherical scoop having a central opening communicating with said pipe. 40
- 5 12. In a suction mouth piece, a suction pipe, a semispherical scoop having a central opening communicating with said pipe, and a cutter adjustably secured to the periphery of said scoop. 45
- 10 13. In a suction mouth piece, a suction pipe, a scoop mounted for rotatable shifting and provided with a series of openings through the body thereof, a valve controlling a port from said scoop, and an operating bar from said valve extended through one of said openings. 50
- 15 14. In a suction mouth piece, a suction pipe, a bearing block mounted thereon and provided with opposite curved faces, and 55 scoops secured to said faces and provided with ports communicating with said suction pipe.
- 20 15. In a suction mouthpiece, a suction pipe, a bearing block mounted thereon and provided with opposite curved faces, scoops 60 secured to said faces and provided with ports communicating with said suction pipe, a pivotal support for said pipe, and an eccentrically disposed operating member secured to said support. 65
- 25 16. In a suction mouthpiece, a suction pipe, a bearing block mounted thereon and provided with opposite curved faces, scoops 70 secured to said faces and provided with ports communicating with said suction pipe, a pivotal support for said pipe, an eccentrically 75

disposed wheel secured to said pipe, and an actuating cable for said wheel having a plurality of strands thereon one of which is secured to said wheel.

17. In a suction mouthpiece, a suction pipe, oppositely disposed scoops having ports communicating with said pipe, a double valve disposed within said pipe, and means for operating said valve. 80

18. In a suction mouthpiece, a suction pipe, oppositely disposed scoops having ports communicating with said pipe, a double valve disposed within said pipe, and a sliding bar mounted to project beyond the 85 face of one of said scoops and connected to said valve. 90

19. In a suction mouthpiece, a suction pipe, oppositely disposed scoops having ports communicating with said pipe, a double valve disposed within said pipe, a sliding bar mounted to project beyond the 95 face of one of said scoops and connected to said valve, and projections from the face of said valve to enter said ports. 100

20. In a suction mouthpiece, a suction pipe comprising an elbow section, pivotal bearings for said section, oscillating means carried by said section, and a scoop member attached to the free end of said section. 105

In testimony whereof I affix my signature in presence of two witnesses.

HORACE J. CLARK.
